B. KRÄMER,
INTERNAL COMBUSTION ENGINE,
APPLICATION FILED JAN. 18, 1913.

1,143,408.

Patented June 15, 1915.

UNITED STATES PATENT OFFICE.

BERNHARD KRÄMER, OF CHARLOTTENBURG, GERMANY, ASSIGNOR TO GENERAL ELECTRIC COMPANY, A CORPORATION OF NEW YORK.

INTERNAL-COMBUSTION ENGINE.

1,143,408.

Specification of Letters Patent. Patented June 15, 1915.

Application filed January 18, 1913. Serial No. 742,827.

To all whom it may concern:

Be it known that I, BERNHARD KRÄMER, a subject of the Emperor of Germany, residing at Charlottenburg, Germany, have invented certain new and useful Improvements in Internal-Combustion Engines, of which the following is a specification.

The present invention relates to internal combustion engines in which fuel is introduced into the combustion chamber either by a pump, a jet of compressed air, or by a combination of both.

Further and more specifically my invention relates to engines in which each charge of fuel is introduced into a body of air whose temperature has been raised by compression to a value above the igniting temperature of the fuel. In such engines where the diameter of the cylinder is large because of the large amount of power they are called upon to deliver, difficulty is experienced in distributing the fuel uniformly through the combustion chamber. That is to say, in some parts of the chamber there will be no fuel, or not enough to combine with the air to form the proper mixture, while in other parts there will be too much to properly combine with the air. In this connection it is to be noted that the time interval in which the fuel can be distributed to form a uniform mixture is exceedingly brief.

My invention has for its object to overcome the objection above noted and to so arrange the parts that a proper and substantially uniform mixture will be obtained at all times.

In the accompanying drawing, which is illustrative of my invention, Figure 1 is a vertical section of an internal combustion engine having opposed pistons in the same cylinder; Fig. 2 is a cross section of the same taken in a plane between the opposed ends of the pistons; Fig. 3 is a similar section of a modified arrangement, and Fig. 4 is a further modification.

5 indicates a cylinder of any suitable construction having pistons 6 and 7. As shown, the engine is of the vertical cylinder type but said cylinders can be arranged horizontally or at any other angle if desired. The cylinder is provided with a water jacket 8 of any suitable construction. The upper part of the cylinder is extended to form a guide 9 for the cross-head member 10 which is attached to the upper piston. This mem-

ber is connected by side rods 11 with the crank 12 on the main shaft. The lower piston is connected with the crank 13 on the main shaft by the connecting rod 14. The cranks 12 and 13 are displaced in this instance by 180 degrees.

Each of the pistons is provided with a curved cut-away portion 15 to form a recess or pocket. This recess terminates in the plane of the end of the piston and also opens into the bore of the cylinder so that the wall of the cylinder cooperates with the curved wall of the recess to form a combustion chamber 15a. As shown the recess in the lower piston registers with that in the upper piston thereby forming a combustion chamber which has one arc shaped surface viewed in elevation and a second arc shaped surface formed by the cylinder wall when viewed in plan.

Fuel is introduced into the combustion chamber by the injector 16 which may be of any suitable construction, said injector receiving its supply of fuel from the pipe 17, the latter communicating with a fuel pump, not shown. The fuel may be injected solely by the pump or by a blast of compressed air in a manner well understood. The portion of the cylinder immediately surrounding the injector may with advantage be cut away, as indicated at 18, to slightly enlarge the combustion chamber. The injector may discharge fuel directly into the combustion chamber or it may be provided with a hemispherical flame plate 19 containing a plurality of radially displaced orifices which serve to distribute the fuel uniformly in the combustion chamber.

The cylinder is provided with exhaust ports 20 and air admitting or scavenging ports 21. These ports are preferably so arranged that they are tangential to the curved surface of the recess in the piston so as to facilitate the passage of the exhaust gases on the one hand, and the introduction of scavenging air on the other. The angular relation or position of these ports will naturally be governed by the curvature of the cut-away portion or portions of the piston.

In Fig. 2 is shown the lower piston 7 having four cut-away portions 15 which are angularly displaced from each other by 90 degrees. In this case four injectors are provided each connecting with its fuel pipe.

In Fig. 3 is shown a slight modification of the invention wherein three fuel injectors are provided. The injectors on the left hand side of the piston discharges into the same combustion chamber 22 while the injector on the right hand side discharges into a combustion chamber which is composed of two parts 23 and 24 with a pointed partition 25 between. The combustion chambers 22, 23 and 24 are of the same general character as that previously described. The fuel on leaving the injector 16 is divided by the partition 25, one portion entering the chamber 23 and the other entering the chamber 24. This arrangement further serves to distribute the fuel uniformly throughout the combustion chamber.

In Fig. 4 is shown a slight modification wherein the combustion chamber 26 is hemispherical in form. This chamber is particularly well adapted for the use of a hemispherical flame plate 19, the peripheral surface of the flame plate and the curved wall of the recess being struck from the same center. This arrangement further requires that the scavenging air port 21 and the exhaust port 20 shall be perpendicular to the axis of the cylinder so that they will be tangential to the curved wall of the combustion chamber. It is to be noted that the distance between the end of the injector and the curved wall of the combustion chamber and the distance between the peripheral surface of the flame plate and the curved wall of the combustion chamber is made small measured in a radial direction, so that the fuel issuing from the injector or flame plate will readily enter all parts of the chamber in order to cause a uniform and thorough mixing of the fuel with the compressed air contained in said chamber. Under some circumstances it is possible to omit the cut-away portions from one of the pistons but as a general proposition it would be found to be more satisfactory to have these recesses in both of the pistons.

It is to be noted that the adjacent ends of the pistons are flat and that when in the inner position very little space is left between them. It is so small in fact that it does not form any real part of the combustion chamber when the pistons are as shown in Fig. 1. Of course a small amount of fuel may enter this space and combine with the highly compressed air therein to form a combustible mixture. Roughly speaking, the cubical contents of the several small combustion chambers should be equal to one-twelfth of the piston displacement. Owing to said small space between the pistons, the pressures in the said chambers will be equalized. The burning products of combustion act of course on the entire surface of the pistons to force them apart.

65 In accordance with the provisions of the

patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In an internal combustion engine, the combination of a cylinder, a piston located therein which is cut-away at its inner end to form a plurality of recesses that open into the cylinder space and coöperate with the wall thereof to form combustion chambers, and separate means for introducing fuel into each of said recesses.

2. In an internal combustion engine, the combination of a cylinder, a piston located therein having parts of its inner end and side cut away at a plurality of spaced points to form recesses, which recesses coöperate with the wall of the cylinder to form combustion chambers, and a fuel injector associated with each chamber.

3. In an internal combustion engine, the combination of a cylinder, oppositely moving pistons located therein, each of said pistons having a part of its inner end and side cut-away to form a recess, the recesses in the two pistons registering and combining with the cylinder wall to form a combustion chamber when the pistons are at the inner ends of their strokes, and an injector for introducing fuel into the chamber, which is located centrally thereof.

4. In an internal combustion engine, the combination of a cylinder, oppositely moving pistons located therein, each of said pistons having a part of its inner end and side cut-away to form a plurality of recesses, the recesses in the two pistons registering and combining with the cylinder wall to form combustion chambers when the pistons are at the inner ends of their strokes, an injector for introducing fuel into each chamber which is located centrally thereof, and a flame plate located at the discharge end of the injectors for distributing the fuel uniformly in said combustion chambers.

5. In an internal combustion engine, the combination of a cylinder, a piston located therein which has a part of its inner end and side cut-away to form a recess, the surface of which is curved, said recess coöperating with the cylinder wall to form a combustion space, means for injecting fuel into the recess, and a port formed in the cylinder wall that is tangentially arranged with respect to the curved surface of the recess to facilitate the passage of gases.

6. In an internal combustion engine, the combination of a cylinder, oppositely moving pistons located therein, each of said pis-

tons having parts of their inner ends and sides cut away at a plurality of spaced points to form recesses, which recesses coöperate with each other and with the wall of the cylinder to form combustion chambers, and a fuel injector associated with each chamber. 15

7. In an internal combustion engine, the combination of a cylinder, a piston located therein having parts of its inner end and 10 side cut away at a plurality of substantially equally spaced points to form recesses, which

recesses coöperate with the wall of the cylinder to form a plurality of substantially equally spaced combustion chambers, and a fuel injector associated with each chamber. 15

In witness whereof, I have hereunto set my hand this 23rd day of December, 1912.

BERNHARD KRÄMER.
